UNITED STATES PATENT OFFICE.

WALTER DE FRIES, OF WILKINSBURG, PENNSYLVANIA, ASSIGNEE TO BLAW-KNOX COMPANY, OF HOBOKEN, PENNSYLVANIA, A CORPORATION OF PENNSYLVANIA.

REVERSING FURNACE AND METHOD OF OPERATING THE SAME.

Application filed December 1, 1920. Serial No. 437,520.

Figure 1 is a vertical section of one end portion of an open-hearth furnace embodying my invention;

Figure 2 is a transverse section taken on the line II—II of Figure 1;

Figures 3 and 4 are, respectively, plan and side elevations showing more or less diagrammatically the actuating connections for the regulators at the two ends of the furnace;

Figures 5 and 6 are sectional views taken respectively on the lines V—V and VI—VI of Figure 1.

My invention has relation to reversing regenerative furnaces, and more particularly to furnaces of this type, such as open-hearth steel furnaces in which gas is used as the fuel.

Heretofore in the construction of furnaces of the type to which my invention relates, the ports at the ends of the furnace have been designed with respect to the double function which they perform, namely, both as intake and outtake ports, it being necessary to use the same port opening for both purposes. As is well known, the volume of the outgoing gases is, due to the expansion, greater than the volume of the incoming air and gas. Therefore, it has been necessary to design ports of a size necessary to take care of the outgoing gases, rather than with respect to their most efficient action as a mixing passage for the incoming air and gas.

The object of my invention is to provide the end ports with regulating means, the position of which can be changed at will, and which will enable each port, during the period that it is being used as an intake port, to function in a more efficient manner with respect to bringing together and mixing the incoming air and gas. The regulators are so arranged that when their position is changed upon reversal of the furnace, they provide a normal port for the offtake of the products of combustion.

The nature of my invention will be best understood by reference to the accompanying drawings, in which I have shown a preferred embodiment thereof and which will now be described, it being premised, however, that the invention is susceptible of various other embodiments and may be widely changed within the spirit and scope of my broader claims.

Referring first to that form of my invention shown in Figures 1, 2, 3, 4, 5 and 6, the

numeral 2 designates a gas uptake at one end 55 of the furnace, 3 an air uptake at the same end of the furnace, and 4 the port into which these uptakes lead and which delivers into the furnace proper, a portion of which is indicated at 5. In accordance with my invention and in the construction shown in these figures, I provide the port 4 at each end with a regulator which can be moved to a position across the port through an opening in the roof wall 6 thereof. This regulator is shown in these figures as consisting of a cage which comprises a water-cooled metal frame 7 of any suitable construction, and which serves to hold in place a refractory body or filler 8. This refractory body is formed with a series of main air ports or passages 9, leading therethrough, and with another series of auxiliary air ports or passages 10, also leading therethrough at a lower level. These two sets of air ports 7 or passages communicate at one end with that position of the port 4 into which the air uptake leads. The said refractory body is also provided with a series of gas ports 11, which have vertical portions 80 communicating with the gas uptake 2, intermediate the secondary air ports 10, and with horizontal portions which discharge into the furnace proper at points above and intermediate the said auxiliary air ports, as indicated at 12. The form and arrangement of these ports will be clearly understood from Figures 1, 2, 5 and 6, although it is to be understood that their particular form and arrangement may be widely modified, to suit the individual requirements for the shape of the flame. The comparatively small air and gas ports in the mixing device or regulator are effective for separately increasing the velocity of the small streams produced. These streams at this high velocity are later brought into contact to produce the desired flame.

The regulator at each end of the furnace is suitably seated, preferably in a water-cooled frame 13, arranged in the walls of each port 4, said frame forming guiding and seating means for the cage and in which the cage can be moved vertically by any suitable means.

Any suitable system of circulating connections, such as those indicated at 14, may be provided for maintaining the circulation of water or other cooling fluid through the seat-

ing and guiding frame, and also through the frame of the regulator. Inasmuch as in the operation of the furnace, the regulator at one end of the port will be in down position, such as shown in Figure 1, while that at the opposite end will be in a raised position, as shown in Figure 4, I preferably connect the two regulators, so that one will act as a counterbalance to the other. This may be done by means of cables 15 (see Figures 3 and 4) which are connected to the respective regulators, and also to a centrally arranged equalizer device 16. To this equalizer are connected the plungers of the two actuating cylinders 17 and 18, one of which is shown at each end of the furnace.

It will be readily understood from Figures 3 and 4 that if one of the regulators is lowered, this lowering action will assist in raising the regulator at the other end of the furnace.

The advantages of my invention will be apparent, since it provides simple and practical means by which the size of the port at the incoming end of the furnace can be made to give the best results in the proper mixing of the air and gas, irrespective of the offtake function of the port, while at the same time, the regulators can be quickly moved to positions in which each port has its full normal cross sectional area when acting as the offtake port. In the form of my invention shown and described, the air and gas passages can be so arranged with respect to each other as to give a most efficient mixing action to the gas and air, prior to combustion, and thus greatly increase the efficiency of the furnace.

I claim:

1. A reversing furnace having a port at each end, with both fuel and air supply connections, and a structure having separate fuel and air ports movable at will into and out of each of said ports, and forming an inlet when in operative position, substantially as described.

2. A reversing furnace having a port provided with both fuel and air connections, and a structure movable at will into and out of operative position in said port, said structure having inlet ports therein separately registering with said connections, substantially as described.

3. In a reversing regenerative furnace, the combination with an end port having air and gas connections leading thereto, of a regulating device movable across said port, said regulating device having air passages communicating with the air uptake and gas passages communicating with the gas uptake, substantially as described.

4. In a reversing regenerative furnace, the combination with an end port having air and gas connections leading thereto, of a regulating device movable across said port, said

regulating device having air passages communicating with the air supply and gas passages communicating with the gas supply, said passages being in alternating relation to each other, substantially as described.

5. In a reversing regenerative furnace, the combination with an end port having air and gas connections leading thereto, of a regulating device movable across said port, said regulating device having air passages communicating with the air supply and gas passages communicating with the gas supply, said passages being in different vertical planes and in alternating relation to each other, substantially as described.

6. In a reversing regenerative furnace, the combination with an end port having gas and air supply passages leading thereto, of a regulator movable across said port, said regulator having a series of gas ports communicating with the gas supply passage and two series of air ports communicating with the air supply passage, substantially as described.

7. In a reversing regenerative furnace, the combination with an end port having gas and air supply passages leading thereto, of a regulator movable across said port, said regulator having a series of gas ports communicating with the gas supply passage and two series of air ports communicating with the air supply passage, one set of air ports being above and the other set being below the gas ports, substantially as described.

8. In a reversing regenerative furnace, the combination with an end port having gas and air supply passages leading thereto, of a regulator movable vertically across said port, said regulator having air and gas port openings therethrough, substantially as described.

9. In a reversing regenerative furnace, the combination with an end port having gas and air passages leading thereto, of a regulator movable at will across said port, said regulator comprising a metallic water-cooled frame and a refractory body or filling, and said regulator having air and gas inlet ports formed therethrough substantially as described.

10. In a reversing regenerative furnace, the combination with an end port having gas and air passages leading thereto, of a regulator movable at will across said port, said regulator comprising a metallic water-cooled frame and a refractory body or filling, and said regulator having a plurality of ports or passages therethrough which communicate respectively with the air and gas supply passages, substantially as described.

11. In a reversing regenerative furnace, the combination with end ports, of regulators, one for each of said ports and movable at will across the respective ports, motive means for shifting said regulators, and a counterbalance connection between the regulators,

each of said regulators having gas and air inlet openings therethrough, substantially as described.

12. In a reversing regenerative furnace, 5 the combination with an end port having gas and air passages leading thereto, of a regulator movable at will across said port, said regulator comprising a metallic water-cooled frame and a refractory body or filling, and 10 said regulator having a plurality of ports or passages therethrough which communicate respectively with the air and gas supply passages and which are so arranged in relation to each other as to give the flame a certain 15 predetermined shape, substantially as described.

13. A reversing furnace having a combined inlet and outlet port, and a member movable at will across said port, said member having a 20 plurality of air and gas ports therein, substantially as described.

14. In a reversing regenerative furnace, the combination with a combined air and fuel inlet and waste gas offtake port, having air, 25 fuel, and waste gas connections leading thereto, of a regulator device movable at will across said port and containing passages for the incoming fuel and air, of a cross-sectional area different from the cross-sectional area of the 30 connections leading from said port and of which the passages form a continuation when the said device is in operating position, substantially as described.

15. The method of operating reversing furnaces, which comprises placing a mixing device in the path of incoming elements of combustion to break up the same into a series of small streams, removing said mixing device, and reversing the furnace, substantially 40 as described.

16. The method of operating reversing furnaces, which comprises placing a mixing device in the path of the incoming elements of combustion to break up the same into a series 45 of small streams, preheating at least one of the elements of the combustion mixture, re-

moving the mixing device, and reversing the furnace, substantially as described.

17. The method of operating reversing furnaces, which comprises placing a mixing device in the path of the incoming elements of combustion to break up the same into a series of small streams, increasing the velocity of said streams, bringing said high velocity streams into contact, removing said mixing device, and reversing the furnace, substantially as described. 50 55

18. The method of operating reversing furnaces, which comprises supplying elements of combustion to a point adjacent the furnace in 60 a plurality of streams, increasing the number of said streams and separately increasing the velocity of said elements, and thereafter bringing said elements into contact with each other within the furnace, substantially as described. 65

19. The method of operating reversing furnaces, which comprises supplying elements of combustion to a point adjacent the furnace in 70 a plurality of streams, preheating at least one of said elements of combustion before it reaches the furnace, separately increasing both the number of streams and the velocity of said elements of combustion, and thereafter bringing said elements into contact with 75 each other within the furnace, substantially as described.

20. The method of operating reversing furnaces, which comprises placing a mixing device in the path of the incoming elements of 80 combustion to break up the same into a series of small streams, preheating at least one of the elements of the combustion mixture, increasing the velocity of said streams, bringing said high velocity streams into contact 85 with each other within the furnace, removing the mixing device, and reversing the furnace, substantially as described.

In testimony whereof, I have hereunto set my hand.

WALTER DE FRIES.
